UNITED STATES PATENT OFFICE

100,087

DESIGN FOR A LAWN SPRINKLER

Savannah B. Butt, Baltimore, Md.

Application April 9, 1936, Serial No. 62,041

Term of patent 7 years

To all whom it may concern:

Be it known that I, Savannah B. Butt, a citizen of the United States, residing at 210 West Mosher Street, Baltimore, Maryland, have invented a new, original, and ornamental Design for a Lawn Sprinkler, of which the following is a specification, reference being had to the accompanying drawing, forming a part thereof.

In the drawing,

The figure is a perspective view of the lawn sprinkler embodying my design.

I claim:

The ornamental design for a lawn sprinkler, as shown.

SAVANNAH B. BUTT.
